UNITED STATES PATENT OFFICE.

MAX KRAUT, OF NEW YORK, N. Y., ASSIGNOR TO NEW ENGLAND PANAMA HAT COMPANY INC., OF NEW YORK, N. Y.

FLEXIBLE STRAW HAT.

Application filed May 7, 1927. Serial No. 189,666.

The object of this invention is to provide a straw hat that is flexible.

A further object of this invention is to provide a straw hat where the inner portion 5 of the brim and lower portion of crown are made flexible.

A further object of this invention is to provide a straw hat where the outer portion 10 of the brim has the braid sewed in circular form and the inner portion of the brim has the braid sewed so that it is perpendicular to the circular braids.

A further object of this invention is to provide a straw hat where I absolutely and 15 entirely eliminate sizing or stiffening processes by the insertion of a straw braid on the inside part of the brim as well as the base part of the crown in a perpendicular manner assuring perfect headform and absolute 20 flexibility that circular straw braid sewing will not yield owing to its inherent nature.

With these and other objects in view, the invention consists in the novel combination and arrangement of parts which will be 25 fully set forth in the following specification and accompanying drawing, in which:

Fig. 1 represents a vertical sectional view of the hat taken on 1—1 of Fig. 2.

Fig. 2, is a view taken from the bottom of 30 the hat.

In the drawing the numeral 1, represents the outer brim made up of upper layer of straw brim 2, and lower layer of straw brim 3, these layers are sewed together in the ordinary manner.

The hat also has the crown 4 sewed together in the ordinary manner.

By the ordinary manner I mean that the braids of the straw hat are sewed in circular 40 fashion.

The hat is made flexible by inserting a connecting portion at the bend of the hat containing a portion of the crown and a portion of the brim and constructed in a novel 45 way.

The crown 4 and brim 1 are connected by means of a flexible brim portion constructed of two layers of straw braid, the outer layer 5 and the inner layer 6. Each layer has the 50 braids sewed together vertically.

The two layers are connected together and sewed to the brim 1, between the upper and

lower layers 2 and 3. The connection to the crown is made only through the outer layer 5. The two layers 5 and 6 are sewed together at 8.

The upper layer 5 has the edges of the straw facing one way, while the lower layer 6, the edges of the straw face the opposite way.

The hat is sized only at the crown and outer brim portion. The insertion 5 and 6 is not sized at all.

The hat is then blocked in the usual manner.

What I claim is:

1. A straw hat comprising a crown and an outer brim portion having the braids sewed in a circular manner, a connecting flexible portion having the braids sewed substantially perpendicular to the circular braids and each braid overlapping the other throughout its length.

2. A straw hat comprising a crown and an outer brim portion having the braids sewed in a circular manner, a connecting flexible portion consisting of two layers of braided straw wherein the braids are substantially perpendicular to the circular braids and each braid overlapping the other throughout its length.

3. A straw hat comprising a crown and an outer brim portion having the braids sewed in a circular manner, a connecting flexible portion consisting of two layers of braided straw wherein the braids are substantially perpendicular to the circular braids, the edging of the connecting braids are faced opposite to each other and each braid overlapping the other throughout its length.

4. A straw hat comprising a crown and an outer brim portion having the braids sewed in a circular manner, a connecting flexible portion having the braids sewed substantially perpendicular to the circular braids and each braid overlapping the other throughout its length, and sizing applied only to top of crown and outer brim portion.

Signed at Brooklyn, N. Y., in the county of Kings and State of New York this 8th day of April A. D. 1927.

MAX KRAUT.
